UNITED STATES PATENT OFFICE

2,612,281

SUPPORT AND STRIPPER

William A. Erhardt, Jr., Philadelphia, Pa., assignor to Conso Fastener Corporation, Philadelphia, Pa., a corporation of New York

Original application December 19, 1946, Serial No. 717,223. Divided and this application April 1, 1949, Serial No. 85,008

4 Claims. (Cl. 218—5)

1

The present invention relates to certain new and useful punch, anvil and stripper mechanism for use in conjunction with or attached to snap-fastener-attaching or grommet-attaching or eyelet-attaching machines, as for instance, the fastener-attaching machines of the United-Carr Fastener Corp. of Cambridge, Mass., exemplified by their Model M-245, and also illustrated in United States Patents Nos. 1,944,510, 2,028,704 and 1,873,890.

An object of the present invention is to provide new and improved punch, anvil and stripper mechanism for attaching snap fasteners, grommets, eyelets or the like.

Other objects and advantages of the present invention are apparent in the following detailed description, appended claims and accompanying drawings.

The present application is a division of my copending application Serial No. 717,223, filed December 19, 1946.

For the purpose of illustrating the invention, there is shown in the accompanying drawing one form thereof which is at present preferred, although it is to be understood that the various instrumentalities of which the invention consists can be variously arranged and organized and that the invention is not limited to the precise arrangements and organizations of the instrumentalities as herein shown and described.

Referring to the accompanying drawings in which like reference characters indicate like parts throughout:

Figure 1 represents a vertical cross-sectional view of an anvil, punch and stripper assembly with the punch shown in uppermost position.

Figure 2 represents a view like that of Figure 1 but with the punch and jaws shown as partly descended.

Figure 3 represents a view like those of Figures 1 and 2 but showing the punch still further descended and the gripping jaws as completely descended.

Figure 4 represents a view like those of Figures 1—3 but showing the punch in lowermost position wherein it has forced the fastener member from the gripping jaws and has locked it to the tape.

Figure 5 represents a view like those of Figures 1—4 but showing the punch in somewhat raised position and indicating the manner in which the jaws strip the fastener member from the ascending punch.

Figure 6 represents a vertical cross-sectional view of a female fastener member and its backing-member just before the two are forced into engagement.

2

Figure 7 represents a view like that of Figure 6 but showing the members fully engaged and attached to the strip material.

Figure 8 represents a vertical cross-sectional view like that of Figure 6 but showing a male fastener member and backing member.

Figure 9 represents a vertical cross-sectional view showing the fastener member and backing member of Figure 8 in engaged position on the strip material.

Figure 10 represents a perspective view showing two pieces of strip material to which male and female fastener members have been attached, respectively, at spaced intervals.

15 The novel anvil, punch and stripper mechanism of the present invention may be applied to any fastener-attaching or similar machine, as exemplified by Model M-245 of the United-Carr Fastener Corp. of Cambridge, Mass. or to any machine adapted to fasten eyelets, grommets, snap fasteners or the like to fabric or similar material, wherein a feeder system automatically and intermittently supplies the engaging elements and the backing elements of the snap-fasteners or the like to the punch and anvil of the machine (which can, if desired, be adjusted for automatically repetitive, intermittent operation).

The attaching machine may be set or adjusted to operate automatically in such manner that grommets or eyelets or fasteners will be applied

30 in rapid succession to any material placed between the punch and anvil of the machine. Although the present embodiment of my invention is shown applied to a United-Carr Fastener Corp. snap-fastener attaching machine Model M-245, it is to be understood that my invention can be applied to other attaching machines. Insofar as any part of the construction or of the mode of operation of the fastener-attaching machine

35 generally shown in the drawings) is not described in detail, it may be assumed to be generally that described in the United States patents of United-Carr Fastener Corp. on their Model M-245 machine (as, for instance, Patents 1,944,510, 2,028,704, 1,873,890 or of any conventional form or construction.

40 In my copending application Serial No. 717,223 referred to hereinabove, there is disclosed a machine for automatically attaching snap-fastener or similar members to a tape of fabric or the like at accurately-spaced intervals. Since the present divisional application is concerned only with the anvil, punch and stripper mechanism, the present drawings are limited to those features and reference is made to my aforesaid

application Serial No. 717,223 for a more detailed description of the remainder of the machine.

As shown in Figures 1-5, the anvil, punch and stripper mechanism includes an anvil 13 and a ram-housing 14 enclosing a reciprocable punch 16 and a pair of reciprocable fastener element gripping jaws 26 for gripping the engaging element (for example a female engaging element 20 of a two-piece snap fastener member 21 shown particularly in Figure 6); the backing element (for example the female backing element 27) being supported on the head 32 of the anvil 13 by opposed jaws 100 and 101. The disposition and operation of these jaws of the anvil are better seen in United States Patent No. 1,944,510.

Appropriate mechanism (not shown) is provided for feeding the engaging elements 20 and the backing elements 27 to the jaws 26 and 100—1 respectively, in a manner more fully described in my aforesaid copending application Serial No. 717,223.

The punch 16 which, as mentioned above, is mounted within the ram housing 14, is constructed and arranged to be driven up or down relative thereto by a crank (not shown). A member 14-a is slidably mounted within the lower end of the ram housing 14 and protrudes downwardly therebeyond. The member 14-a is provided with a central axial opening into which the punch 16 extends with a relatively tight fit whereby downward movement of the punch 16 will tend to carry the member 14-a along with it, until the upper flange of the member 14-a strikes the inwardly extending annular flange 14-c at the bottom of the ram housing 14. This type of frictional drive for the member 14-a is conventional in the art and is disclosed, for example, in Patents 1,873,890 and 1,944,510.

Member 14-a carries the two jaws 26 at the lower end thereof, and when the member 14-a is in its uppermost position (as shown in Figure 1) the grooves 26-a are in position to receive a female engaging element 20 from suitable feeding mechanism (not shown). At the start of a cycle, the driving means causes the punch 16 and the jaw-carrying member 14-a to descend simultaneously relative to the stationary ram-housing 14 to the position shown in Figure 2.

In the position shown in Figure 3 the jaw-carrying member 14-a has been arrested in its downward travel by the limiting flanges 14-c formed at the bottom of the ram-housing 14, but the punch 16 has continued to descend so as to approach the element 20. Further downward movement of the punch 16 pushes its tip 16-a through the opening 20-a of the element 20, after which the element is forced through the grooves 26-a and the jaws 26 onto the tape 22. The jaws 26 are designed to pivot (in the direction of the arrows in Figure 1), about the annular shoulder 14-d of the member 14-a when the punch forces the element 20 from the groove 26-a; compression springs 14-e tending to resist this pivoting action. In the position shown in Figure 4, the punch 16 has forced the element 20 against the tape 22 and into contact with the backing element 27 with sufficient force to cause the prongs 27-a of the element 27 to pierce the tape 22 and lock within the element 20 in the manner disclosed particularly in Figure 7, thereby permanently to mount the snap-fastener member 21 to the tape 22.

This clinching action also causes the edges of the opening 20-a of the engaging element 20 tightly to grip the tip 16-a of the punch 16 so

that the fastener element 21 has a tendency to be held frictionally upon the tip 16-a when the punch 16 begins its subsequent ascent.

However, as soon as the element 20 has been displaced from the groove 26-a by the punch 16, the jaws 26 snap back (under the action of the springs 14-e) toward each other (i. e. opposite the direction of the arrows of Figure 1) so that the jaws bear against the neck 16-b of the punch 16 and provide insufficient clearance for the engaged fastener member 21 to pass upward therebetween.

In the position shown in Figure 5, the punch 16 has begun its ascent, bringing the top side of the element 20 (which, as mentioned above, clings to the punch-tip 16-a) into contact with the under-surface of the jaws 26. During this preliminary ascent of the punch 16 the jaw-carrying member 14-a is kept from rising by a spring-actuated ball-stop 110 which overlaps the uppermost shoulder of the jaw-carrying member 14-a and prevents the member 14-a from rising relative to the ram-housing 14 until pushed upward by a force greater than the frictional restraining force exerted by the ball-stop 110. The ball-stop 110 temporarily prevents upward movement of the flange of the jaw-carrying member 14-a, even though the earlier downward movement of said flange past said ball-stop was not retarded or impeded because a chamfer 111 on the lower edge of the flange of said jaw-carrying member 14-a cammed the ball-stop 110 inwardly to permit the passage of the flange.

In this way, the contracted jaws 26 strip the fastener member 21 from the punch-tip 16-a after only a very slight upward movement of the attached fastener and the tape.

However, when the pin 16-c carried by the punch 16 rises and strikes the surface 16-d of the member 14-a, the positive upward force imparted to the member 14-a overcomes the frictional retarding action of the ball-stop 110, after which the member 14-a moves upward with the punch 16 to the starting position shown in Figure 1 so as to complete the cycle.

Thereafter, another engaging element 20 is fed to the jaws 26 and another backing element 27 is fed to the jaws 100—1 and the cycle is repeated; the tape 22 advancing, in the meantime, to a new position, by mechanism disclosed in my aforesaid copending application Serial No. 717,223, so that the next snap fastener is mounted on the tape at a predetermined distance from the preceding one.

It is also possible to attach male snap fasteners consisting of a headed male engaging member 28 and a corresponding backing member 29 shown particularly in Figure 8; the assembled position of the elements 28 and 29 being shown in Figure 9.

It is also possible to attach grommets, eyelets and the like by simply changing the size and shape of the engaging and supporting surfaces of the jaws 26 and 100—1 and the anvil head 32 in a manner well known to those skilled in the art.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described my invention, I claim as new and desire to protect by Letters Patent:

1. In a machine for attaching grommets, eye-

lets, snap-fasteners or like elements to a tape or the like; a downwardly-directed vertically reciprocal punch, a ram-housing, a jaw-carrying slide vertically movable within said housing, said slide having a central opening through which said punch extends, said slide being constructed and arranged to move downwardly with said punch during the punching stroke, a pair of cooperating jaws pivotally carried by said slide and having opposed gripping surfaces formed thereon, means for feeding an individual element into position intermediate the opposed gripping surfaces of said jaws and in line with said punch, said opposed gripping surfaces being somewhat spread apart by said element, a stationary anvil disposed below said gripping surfaces and in line with said punch, said anvil being constructed and arranged to hold a complementary element in vertical alignment with the first-mentioned element, downward movement of said punch on its punching stroke causing the lower end of the punch to move from a point above said opposed gripping surfaces to a point below said gripping surfaces thereby to engage said first-mentioned element and thereafter to force it downward from between the said opposed gripping surfaces and into locking engagement with said complementary element carried by the anvil, said jaws being constructed and arranged to pivot when said first-mentioned element is displaced so as to bring the jaws closer together and into overlying relationship to the displaced element, and stop-means for delaying the return movement of said slide and said jaws during the upward return movement of said punch until after the lower end of the punch has returned to a point above said gripping surfaces whereby the contracted ends of the jaws prevent the displaced element from moving upward any substantial distance with said punch and thereby serve to strip said element from said punch.

2. In a machine for attaching grommets, eyelets, snap-fasteners or like elements to a tape or the like; a downwardly-directed vertically reciprocal punch, a ram-housing, a jaw-carrying slide vertically movable within said housing, said slide having a central opening through which said punch extends, said slide being constructed and arranged to move downward with said punch during the punching stroke, a pair of cooperating jaws pivotally carried by said slide and having opposed gripping surfaces formed thereon, means for feeding an individual element into position intermediate the opposed gripping surfaces of said jaws and in line with said punch, said opposed gripping surfaces being somewhat spread apart by said element, a stationary anvil disposed

below said gripping surfaces and in line with said punch, said anvil being constructed and arranged to hold a complementary element in vertical alignment with the first-mentioned element, downward movement of said punch on its punching stroke causing the lower end of the punch to move from a point above said opposed gripping surfaces to a point below said gripping surfaces thereby to engage said first-mentioned element and thereafter to force it downward from between the said opposed gripping surfaces and into locking engagement with said complementary element carried by the anvil, said jaws being spring-urged to pivot when said first-mentioned element is displaced so as to bring the jaws closer together and into overlying relationship to the displaced element, yieldable stop-means for delaying the return movement of said slide and said jaws during the upward return movement of said punch until after the lower end of the punch has returned to a point above said gripping surfaces whereby the contracted ends of the jaws prevent the displaced element from moving upward any substantial distance with said punch and thereby serve to strip said element from said punch, and connecting means for thereafter positively moving said slide with said punch on the return movement thereof so as to overcome the restraint of the yieldable stop-means.

3. A construction according to claim 2 wherein the yieldable stop-means comprises a spring-tensioned ball-check carried by said housing and yieldably extending into the path of travel of the slide and wherein the connecting means comprises a pin carried by the punch and protruding within a vertical groove extending part way along the central opening of the slide.

4. A construction according to claim 2 wherein the lower portion of the punch has a reduced-diameter less than the distance between the said opposed gripping surfaces when an element is supported thereby, and wherein the contracted jaws bear against the reduced-diameter lower portion of the punch when the first-mentioned element has been removed from between the opposed gripping surfaces thereof.
